UNITED STATES PATENT OFFICE

ALBERT H. SCHMIDTKE, OF ST. JOSEPH, MICHIGAN, ASSIGNOR TO ST. JOSEPH IRON WORKS, OF ST. JOSEPH, MICHIGAN

BOX MAKING MACHINE

Application filed March 3, 1930. Serial No. 432,953.

This invention relates to improvements in box making machines.

The objects of this invention are:

First, particularly to provide a quick and effective machine for making orange crates or boxes.

Second, to provide such a structure admitting of rapid and convenient manipulation of such a box or crate.

10 Objects pertaining to details and economies of construction and operation of my invention will appear from the description to follow.

The invention is defined and pointed out 15 in the claims.

A structure which is a preferred embodiment of my invention is illustrated in the accompanying drawings, in which:

Fig. 1 is a perspective view of the rear 20 side of the machine showing the control of the clamping jaws and the means for feeding them back and forth.

Fig. 2 is an enlarged detail vertical sectional elevation taken on the line 2—2 of 25 Fig. 3.

Fig. 3 is a detail horizontal sectional plan view taken on line 3—3 of Fig. 2.

Fig. 4 is a perspective view of one of the 30 orange boxes or crates.

The parts will be identified by their numerals of reference which are the same in 35 all the views.

1 is the base of the machine on which are disposed end uprights, 2, 3 connected at the 40 top by a supporting cross bar 4.

5 is the crosshead carrying a series of stapling headers 6, 6 adapted to drive staples in pairs through the side slats of the crate or box into the ends and central partition.

40 The box is made up of ends 7 and 8 and a mid-partition 9 which are connected by slats 10 to form the sides and bottom, the top being left open, as seen in Fig. 4.

A cross member 11 is supported between 45 the end uprights 2 and 3 and to this are secured supports 12 with forwardly extending portions 121 to receive the end members of the box in upright position. A central support 13 is provided with a forwardly extending portion 131 to receive the mid-

partition 9 of the box or crate. In Fig. 3 the partitions 7, 8 and 9 are shown in position on these supports.

A fixed shaft 14 connects the two side members and affords supports for the fixed 55 jaws 15, 16 and 17.

A rockshaft 18 is disposed parallel to the fixed shaft 14 and is carried by brackets 19, 20 having bearings 191 and 201 for the end of the shaft 18.

The jaws 15, 16 and 17 have rear extensions 151, 161, and 171 with bearings 152 65 162 and 172 for the said rock shaft 18 and by this means the clamping jaws 15, 16 and 17 are effectively supported in position.

Sliding jaws 21, 22 and 23 are disposed to slide freely on both the fixed shaft 14 and the rockshaft 18, the same being provided with rear extensions 211, 221 and 231 respectively and having bearings 212, 222 70 and 232 which embrace the said rockshaft 18.

Springs 24 are provided and connected to hold these movable jaws in open position, being connected at one end to the jaw and 75 at the opposite end to suitable hooks on the frame or any part of the machine.

Cam arms 25, one for each movable jaw, are provided on the rockshaft 18 and on each jaw 21, 22 and 23 is a cam roller 26 co-operating with the corresponding cam 25 for closing and clamping the jaws against the ends and mid-partition of the box.

The main driving shaft 27 carries eccentrics 271 at each end which are connected by 85 pitmen 273 to the crossheads 5 for reciprocating the staplers. The main drive shaft 27 is also provided with an eccentric 274 which carries a connection 275 which connects to rockshaft arm 181 for controlling the action of the clamping jaws so that it will be observed that on each reciprocation of the stapling head, the clamping jaws are operated to hold the work and the clamping jaws are immediately released after the 90 stapling is accomplished.

The position of the work in the clamping jaws is controlled by a suitable ejector means which, after the nailing or stapling of the first slat, partially ejects the box when 100

the second slat is stapled or nailed. This consists of an ejector head 28 having ejecting plungers 281, 282 which pass through guides 283 carried by the fixed jaws 15 and 16, being detailed particularly in Fig. 2. The ejector is actuated by a cam 29 carried on a shaft 291 supported at the ends of the brackets 19, 20. The head 28 is provided with a projecting member 284 containing a slot 285 which embraces roller 292 on the shaft 291. The member 28 is also provided with cam abutments 286 and 287 which co-operate with the oblong cam 29 to reciprocate and actuate the ejector.

The cam shaft 291 is driven from sprocket wheel 276 on the main shaft 27 which connects by a sprocket chain 277 to sprocket wheel 293 on the said cam shaft 291, the same being geared in the ratio of one to two so that the cam shaft is turned half over at each revolution of the main shaft 27, the cam 29 having a suitable dwell 294 so that the work remains stationary during the operation of the stapling heads.

The ejector heads are urged in by means of springs 295 which facilitates their operation.

The mechanism is driven by any suitable gear means 30 not necessary to detail here as such are in use on machines of this type to give them the necessary intermittent movement for the operations required. The machine operates with great facility as will be seen by a consideration of its movements.

The operator places the box ends 7 and 8 and the mid-partition 9 in the work jaws with the machine set in the position as indicated in Fig. 2. A pair of slats 10 are then put in position and the machine is thrown in gear to operate. The crosshead 5 descends carrying the staplers 6, 6 down and putting a pair of staples at each end of the partition, stapling the front slats securely in place. Continued evolution of the machine throws the cam shaft 291 and operates the cam 29 which throws the ejector plungers 281, 282 at each end against the ends 7 and 8, carrying them out so that the rear slat comes into proper position for stapling. The stapling movement is then completed and the continued evolution of the machine withdraws the ejectors to the "in" or initial position indicated in Fig. 2 and the stapler is raised. No ejector is needed for the central partition 9 as it is carried along because it is stapled to the center of the slat. When the first two slats at one side are stapled, the box or crate is turned down on its top and the evolution is repeated which staples the bottom slats in place. The box is then turned down on its side and another evolution of the machine completes the second side of the box, thus putting on the two sides and bottom and leaving the top open. The machine thus works with great rapidity.

Of course, it could be operated without putting in this central partition and the machine could be operated for making a very great variety of boxes or crates as a consequence.

It is especially desirable for and I desire to claim it especially as an orange crate machine and also to claim it broadly as pointed out in the appended claims.

Having thus described my invention, what I claim as new and desire to secure by Letters Patent is:

1. In a machine of the class described, the combination of a suitable base, end uprights connected at the top, a reciprocating carrier head in guides on the said uprights, staple drivers carried by the said head disposed to drive staples into a box therebeneath, end supports for receiving the box ends to support them while being stapled, an intermediate support for the central box partition, a fixed shaft between the said uprights, brackets at each end, a rockshaft carried by the said brackets, fixed jaws clamped to the said fixed shaft and with extension bearings embracing the rockshaft, slideable clamping jaws on said shafts to coact with the fixed jaws with springs for holding them yieldingly in open position, cam arms on the said rockshaft disposed to act upon the slideable jaws, cam rollers on said slideable jaws to coact with the said cam arms, an ejector head at each end of the machine with an ejector plunger guided for ejecting and controlling the movement of the said box ends, oblong cams on a suitable cam shaft carried by the said brackets in parallel relation to the rockshaft and fixed shaft, a slotted guide projection on each of the said ejector heads and having cam abutments for cooperating with the said cams, the said cams each being provided with a dwell to hold the box at rest while it is being clamped and stapled, a drive shaft, a gear on said shaft to drive the cam shaft at one half the rate of the drive shaft, eccentrics at each end of the drive shaft with connections for reciprocating the carrier head, and an intermediate eccentric on said drive shaft with a connection to said rockshaft timed to actuate the jaws and clamp the work while the same is being stapled.

2. In a machine of the class described, the combination of a suitable base, end uprights connected at the top, a reciprocating carrier head in guides on the said uprights, fastener inserting drivers carried by the said head disposed to drive fasteners into a box therebeneath, end supports for receiving the box ends to support them while the fasteners are being inserted, an intermediate support for the central box partition, a fixed shaft between the said uprights, brackets at each end, a rockshaft carried by the said brackets, fixed jaws clamped to the said fixed shaft

and with extension bearings embracing the rockshaft, slideable clamping jaws on said shafts to coact with the fixed jaws with springs for holding them yieldingly in open position, cam arms on the said rockshaft disposed to act upon the slideable jaws, cam rollers on said slideable jaws to coact with the said cam arms, an ejector head at each end of the machine with an ejector plunger guided for ejecting and controlling the movement of the said box ends, a drive shaft, gear drive means thereon for operating the ejector plungers, eccentrics at each end of the drive shaft with connections for reciprocating the carrier head, and an intermediate eccentric with a connection to the rockshaft timed to actuate the jaws and clamp the work while the fasteners are being inserted.

3. In a machine of the class described, the combination of a suitable base, end uprights connected at the top, a reciprocating carrier head in guides on the said uprights, fastener inserting drivers carried by the said head disposed to drive fasteners into a box therebeneath, end supports for receiving the box ends to support them while the fasteners are being inserted, fixed and movable clamping jaws at each end for holding the box ends, an ejector head at each end of the machine with an ejector plunger guided for ejecting and controlling the movement of the said box ends, oblong cams on a suitable cross cam shaft carried by brackets in parallel relation to the main shaft, a slotted guide projection on the said ejector head and having cam abutments for cooperating with the said cams, the said cams each being provided with a dwell to hold the box at rest while it is being clamped and the fasteners inserted, a main drive shaft, a gear on said shaft to drive the cam shaft at one-half the rate of the drive shaft, eccentrics at each end with connections for reciprocating the carrier head, and an intermediate eccentric with connection timed to actuate the jaws and clamp the work while the fasteners are being inserted.

4. In a machine of the class described, the combination of a main framework, a reciprocating carrier head in guides on the said framework with fastener inserting drivers carried by the said head and supports for receiving the box ends to support them while the fasteners are being inserted, clamping jaws to hold the box ends in place, an ejector head at each end of the machine with plungers to partially eject the said box ends from the jaws, cam means for actuating the said ejector, a main drive shaft, a gear on said main shaft connected to drive the cam shaft at one-half the rate thereof, connections on the said shaft for reciprocating the carrier head, and eccentric connections on the said shaft for operating the clamping

jaws timed to clamp the box while the fasteners are being inserted and to release the jaws while the box is being partially ejected.

5. In a machine of the class described, the combination of a main framework, a reciprocating carrier head in guides on the said framework with fastener inserting drivers carried by the said head and supports for receiving the box ends to support them while the fasteners are being inserted, clamping jaws to hold the box ends in place, an ejector head at each end of the machine with plungers to partially eject the said box ends from the jaws, cam means for actuating the said ejector, connections on the said shaft for reciprocating the carrier head, and eccentric connections on the said shaft for operating the clamping jaws timed to clamp the box while the fasteners are inserted and to release the jaws while the box is being partially ejected.

6. In a machine of the class described, the combination of a reciprocating fastener inserting head, guiding supports disposed beneath the box ends, clamping jaws for holding the box ends in position while the fasteners are inserted, means for releasing the jaws after each fastener inserting operation, an ejector means to partially eject the box ends after the initial fastener inserting operation, and an intermittently operated drive shaft with timed connections to clamp the box, operate the head, release the jaws and partially eject the box end.

7. In a machine of the class described, the combination of a reciprocating fastener inserting head, guiding supports disposed beneath the box ends, clamping jaws for holding the box ends in position while the fasteners are being inserted, means for releasing the jaws after each fastener inserting operation, an ejector means to partially eject the box ends after the initial fastener inserting operation, and an intermittently operated drive shaft with timed connections to clamp the box, operate the head, and release the jaws.

In witness whereof I have hereunto set my hand.

ALBERT H. SCHMIDTKE.
